US0D1102090S

(12) **United States Design Patent** (10) Patent No.: **US D1,102,090 S**
(45) Date of Patent: ** Nov. 18, 2025

(54) **BABY CLOTHING**

(71) Applicant: **petit cochon Manufaktur GmbH**,
Berlin (DE)

(72) Inventors: **Selina Schweiker**, Berlin (DE);
Friederike Sirin, Berlin (DE)

(73) Assignee: **PETIT COCHON MANUFAKTUR
GMBH**, Berlin (DE)

(**) Term: **15 Years**

(21) Appl. No.: **29/876,756**

(22) Filed: **May 26, 2023**

(30) **Foreign Application Priority Data**
